MEANS FOR SUPPORTING AND ADJUSTING
DRAPERIES

Douglas R. Falkenberg, Lakewood, Ohio

Application June 22, 1948, Serial No. 34,404

5 Claims. (Cl. 211—105.2)

1

The invention relates to means for supporting and adjusting draperies, and particularly to devices of this character utilized for dependingly supporting draperies in a vertically pleated arrangement, and for adjusting the pleated draperies to maintain the desired supporting position.

The objects of the invention are to provide a supporting member for such draperies to and from which the upper end of the drapery may be quickly and conveniently attached and removed, in which an ornamental pleating of the depending drapery may be quickly effected and without the necessity of the hanger being an experienced pleater, and in which an adjustment of the drapery supporting rod may be quickly and conveniently effected for maintaining the proper balance or alignment of the several pleats of the depending drapery.

The claims of the instant application are limited to the means for supporting and adjusting draperies.

The annexed drawings and the following description set forth in detail certain means illustrating the improvements in means for supporting and adjusting draperies; such disclosed means constituting, however, only a few of the many forms in which the principle of the invention may be embodied.

In said annexed drawings:

Figure 1 is a front elevation of a fragmentary portion of a window frame to which is secured an improved drapery rod forming part of the instant invention and from which depends a pleated drapery;

Figure 2 is a top plan of the elements shown in Figure 1;

Figure 3 is a vertical section, upon an enlarged scale, taken in the plane indicated by the line 3—3, Figure 2;

Figure 4 is a fragmentary plan view of a slightly modified form of improved drapery rod upon which has been partially threaded a drapery designed to be dependently supported by the rod;

Figure 5 is a fragmentary top plan view, upon an enlarged scale and partially in horizontal section, of the inner end of the rod shown in Figure 2;

Figure 7 is a bottom plan view;

Figure 8 is a side elevation looking from the left end of Figure 5;

Figure 9 is a rear elevation of the elements shown in Figure 5;

Figures 10 and 11 are, respectively, a top plan view and a front elevation of a certain adjustable

2

element serving as part of the means to maintain the various pleated portions of the drapery in balance and in desired alignment;

Figures 12 and 13 are, respectively, a top plan and a side elevation of a pivoted finger serving to actuate the adjustable element shown in Figures 10 and 11;

Figure 14 is an axial section, taken in the planes indicated by the line 14—14, Figure 5;

Figure 15 is a fragmentary horizontal section, taken in the planes indicated by the line 15—15, Figure 8, showing the joint between the window-frame part of the drapery rod and the part there-over which the drapery is threaded;

Figure 16 is a detail of the window-frame part of the elements shown in Figure 15, showing a shoulder thereon for engagement with a flat portion of the drapery-engaging part; and

Figure 17 is an exploded view of the joint parts 20 of the structure shown in Figure 15, particularly showing the engageable shoulder and flat.

Referring to the annexed drawings in which the same parts are indicated by the same respective numbers in the several views, a rod 3 forming a supporting bracket for the improved supporting and adjusting means is secured in horizontal position by spaced holes 31 and screws 32 to the top of a window frame 1 and extends interiorly thereof any desired distance over the window opening. The portion 4 of the supporting and pleating means which is adjustable is a sinuous formation 4 having alternately inwardly and outwardly directed loops 42 entrance to which is obtained by slots 5 of substantial width but materially smaller than the width of the loops 42 so that each part of the sinuous formation 4 simulates in top plan one-half of an hour-glass formation. The interiorly-extended end of the rod 3 is secured to one end of an intermediate relatively-right-angular formation 6, Figures 2 and 5, whose opposite end is secured to one end of the sinuous formation 4. The other end of the formation 4 is formed into a hook member 44, Figures 1 and 2.

The relatively right-angular formation 6 and the sinuous formation 4 comprise the draping member, the member 6 providing what is known in the trade as the "extension," i. e., the distance inwardly of the supporting rod or bracket 3 at 50 which the draped material depends.

The material 2 to be draped is provided with a deep upper-end rear hem 21 forming a horizontal passage 22 therethrough, Figure 3. The rod member 4 and the relatively angular formation 6 of the draping member are threaded through

the material 2 to be draped.

the passage 2² by passing the drapery material 2 over the member 4, commencing at the hooked end 4¹, as illustrated in Figure 4, so that the drapery material 2 encloses the rod part 4 and also the angular part 6, as illustrated in Figures 1 and 2. The drapery thus depends from the rod part 4 and formation 6, as shown in Figures 1 and 3, and a balanced ornamental pleating of the drapery 2 can be easily and conveniently effected by suitably manipulating the drapery portions enclosing the various rod parts 4² and member 6. Each supporting structure and the drapery depending therefrom are designed to serve one-half of a window.

Two adjustments of the supporting structure are particularly desirable in order to obtain and maintain the desired hanging of the drapery material, one of these adjustments involving the extent to which the inner end of the rod or bracket part 3 and, hence, the inner edge of the hanging 2 overlaps the window pane. Such adjustment is effected by securing the rod part 3 in such inner adjusted position as desired by a fastening thereof to the window frame 1 by means of selected screw holes 3¹ and screws 3².

The second important adjustment involves maintaining the proper alignment in a horizontal plane of the several portions of the pleated drapery enclosing the loops 4². This is a highly important adjustment inasmuch as the drapery material may be quite heavy and hangs upon a part of the drapery rod which has a free unsupported end and, hence, may be caused to sag. This adjustment and the connection of the window-frame part 3 of the rod to the looped part 4 are effected by the following elements:

A plain terminal part at the inner end of the rod 3 is bent into an intermediate eyelet formation 7 and the end thereof secured by a rivet 7¹ to a side of the channel 3, the eyelet 7 receiving a depending cylindrical end portion 9 of a housing part 8 of the angular formation 6, Figures 5, 8, 14, and 15. From a vertical plane adjacent the eyelet 7, the lower part of the housing 8 is of bifurcated formation, Figures 8 and 15, the two depending wings 8¹ of which are secured together at their free ends by a rivet 17, Figures 5 and 14. This bifurcated formation forms a slot 16 below the solid upper part of the housing 8, which slot 16 has an elongated bottom opening intersecting the bottom face of the housing 8.

Threadedly engaging the wings 8¹ of the housing 8 at 8² and intersecting the slot 16 is an upwardly-directed screw 12, Figure 14, having a bottom end finger piece or knob 12¹, and engaging the upper end 12² of the screw 12 is the tail piece 11 of a finger 10 which is pivoted, adjacent the screw 12, upon a rivet 20 passed through the housing wings 8¹. The opposite end 13 of the finger 10 is semi-spherical and engages the walls of a recess 15 formed in one end of a member 14 pivoted on the rivet 17. The member 14 is an integral angular end portion of the innermost rod loop 4², Figures 5, 10, 11, and 14, and passes through an opening in the free end of the housing 8. The adjusting end 13 of the finger 10 rolls on a curved inner end wall 15¹ of the recess 15 of the adjusting member 14, as clearly appears in Figures 11 and 14. Hence, it is evident, that manipulation of the screw 12 in the lower unobstructed part of the passage 2², Figure 3, of the drapery 2 will raise or lower the pleating and supporting member 4 and provide means for maintaining the alignment of the several pleat-

ed parts of the drapery 2 as required or as is desirable.

The cylindrical end portion 9 of the draping member part 6 is not rotatable in the eyelet 7 since the housing 8 is formed adjacent the cylindrical end portion 9 with a bottom face flat portion 18 which, when engaging the cylindrical member 9 with the eyelet 7, is dropped on a shoulder member 19 formed on the top of the inner portion of the eyelet 7, as particularly shown in Figures 16 and 17.

The structure which has thus far been described provides a pleating formation, particularly illustrated in Figures 1 and 2, in which there is a space 21 between the faces of a pleat at the rear, governed by the width of the slots 5 but such showing is only illustrative and other pleating formations may be selected, if desired, as will now be illustrated by reference to Figure 4.

Figure 4 which illustrates the manner of threading the drapery material on the supported sinuous and relatively angular parts of the draping member to effect the pleated formation also shows a modification in which the slots 5² providing openings into the several looped formations 5³ are relatively narrow so that if a drapery of stiffer material is threaded on the pleating member 5¹, the adjacent portions of the material of adjacent loops will fill the slots 5² and close them so that the pleats will be tubular in cross section. This engagement of the adjacent material portions will not be so rigid as to prevent manipulation thereof into the desired position but will serve to retain the several pleats of the draped material in adjusted position, after the material has once been adjusted.

What I claim is:

1. Means for supporting and adjusting draperies, comprising a supporting bracket and a draping member, the latter having a part providing an extension relatively angular to the supporting bracket and a part substantially parallel to the supporting bracket, the draping member including a bifurcated housing mounted on the supporting bracket, the parallel draping member part having a pivotal mounting in the housing, and a member for maintaining said parallel draping member part in substantially horizontal position comprising a finger pivotally mounted intermediate its ends in the housing between the bifurcated parts thereof and engaging said parallel draping member part at one end of the finger for movement of the parallel draping member part in a substantially vertical plane, and an actuating member engaging the opposite end of the finger, passed through the opening between the housing parts, and having screw-threaded engagement with said housing parts.

2. Means for supporting and adjusting draperies, characterized as in claim 1, in which the housing has a closed top, open bottom, and opposed spaced side wings, and in which the actuating member intersects the open bottom of the housing and threadedly engages the side wings thereof.

3. Means for supporting and adjusting draperies, characterized as in claim 1, in which the engaging end of the finger and the portion of the parallel draping member part engaged thereby have means for rolling engagement of the finger end on said draping member part.

4. Means for supporting and adjusting draperies, characterized as in claim 1, in which the supporting bracket has a looped end portion, in which the housing of the draping member has a

projecting cylindrical portion snugly engaging the loop of the supporting bracket, and in which means are provided preventing the relative turning of the cylindrical portion and the loop.

5. Means for supporting and adjusting draperies, comprising a supporting bracket and a draping member non-rotatably mounted on the bracket and having a part substantially relatively right-angular to the supporting bracket and also a part substantially parallel to the supporting bracket, the right-angular draping member part having an open bottom bifurcated housing in which the parallel draping member part is pivotally mounted for adjustment in a vertical plane, and means for effecting the adjustment of the parallel draping member part comprising a manually-operable member intersecting the open bottom of the housing, having screw-threaded engagement with the latter, and having means

engaging the inner end of the adjustable draping member part.
